UNITED STATES PATENT OFFICE.

SAMUEL MCCLURE AND CHARLES F. PHILLIPS, OF SHARON, PENNSYLVANIA.

DEVICE FOR PROTECTING FURNACES OR LIKE STRUCTURES.

SPECIFICATION forming part of Letters Patent No. 397,376, dated February 5, 1889.

Application filed March 1, 1888. Serial No. 265,878. (No model.)

To all whom it may concern:

Be it known that we, SAMUEL MCCLURE and CHARLES F. PHILLIPS, citizens of the United States, residing at Sharon, in the county of Mercer and State of Pennsylvania, have invented certain new and useful Improvements in Devices for Protecting Furnaces or Like Structures; and we do hereby declare the following to be a full, clear, and exact description of the invention, such as will enable others skilled in the art to which it appertains to make and use the same.

Our invention relates to means for protecting the linings and jackets of furnaces and furnace-stacks. It is applicable to all classes of furnaces—such, for instance, as blast, puddling, heating, and cupola furnaces—and to all classes of stacks, whether constructed of brick and iron or of brick alone.

The invention consists, first, in providing a brick structure—such as a furnace or stack—with a non-conducting water-space filled with gravel or other coarse substance; further, in the peculiar arrangement of devices for supplying water to the whole or to any part of such water-space; further, to a system of "observation-boxes" located in the wall of the structure, by means of which the condition of the water-space and furnace-lining may be observed, and, finally, in details of construction required in embodying the above general features, all of which will be fully hereinafter described.

Figure 1 represents a vertical section through the wall or lining of a blast-furnace. Fig. 2 is a similar section, illustrating a modification. Fig. 3 is a horizontal section on the line *x x* of Fig. 1. Fig. 4 is a plan view of a section of the water-pipe within the water-space. Fig. 5 is an elevation of one of the observation-boxes.

As stated above, our invention is applicable to all kinds of brick furnaces and furnace-stacks; but we have shown it in the drawings in connection with a blast-furnace of the ordinary type, the drawings showing only so much of such a furnace as is necessary to fully illustrate our improvements.

A is the inner brick structure or lining of the furnace, and B the external iron jacket surrounding said furnace.

C represents a space in the lining, which

extends from the cap or mantel D to the top of the furnace and throughout the entire extent of the latter, as shown in Fig. 3. This space may be formed as in Fig. 1, where an external course of brick is interposed between it and the jacket B, or as in Fig. 2, where the space is formed between the jacket and brick-work directly. The entire space is filled with coarse gravel or some similar material, which of itself forms a non-conducting agent. This non-conducting space is supplied with water in whole or in any portion by a system of water-distribution, which will now be described.

E represents a water-pipe constructed in sections *b*, as shown in Fig. 3. This pipe is embedded in the gravel filling of the water-space at a suitable height and extends horizontally throughout the entire circumference of said space. The ends of the sections are closed and each one is provided with a number of perforations, *b'*, Fig. 4, through which the water is admitted to the gravel filling, down which it percolates, thoroughly moistening it below each section of pipe. The sections *b* may be supplied with water from a circular pipe, F, surrounding the furnace and having a branch pipe, *f*, with a suitable valve, *f'*, communicating with each of said sections. A vertical pipe, G, communicates with said pipe F and with a tube, H, connected to any supply of water under pressure. We prefer, however, to dispense with the pipe F, and supply each section *b* by means of a separate vertical pipe, like the pipe G, connected directly to such section and to the tube H and having a suitable cut-off valve. The tube H also surrounds the furnace and is supported by the bracket I. The tube is preferably made, as shown in Figs. 1 and 2, with an open trough, J, into which the discharge-pipe K carries any excess of water from the space C, and which should communicate with a suitable drain. The tube and trough are built of iron sections bolted together, as shown at *i*, Fig. 1, but may be formed in any other way that may be found desirable.

It will be evident from the description that water can be supplied to any or all of the sections *b* of the inner water-pipe, and thus that any portion of the entire circumference of the gravelled space may be thoroughly moistened at will; also that the water may be shut off

entirely and such space used as a dry non-conductor.

In order that the condition of the furnace-lining and water-space may be accurately observed, we have provided a series of observation-boxes, L, one of which is shown in Fig. 5. These boxes are cast of any desired size—say from four to six inches in diameter—and are preferably square in cross-section. They are cast with a flange, l, at their outer end, by means of which they are bolted to and within the iron furnace-jacket, as shown at l', Fig. 1. Their inner end extends a sufficient distance into the brick lining, and, like the outer end, is open, so that the condition of the lining can be seen. Each box is provided with a slot, l², which registers with the water-space, and which, while allowing the amount of moisture in the gravel to be ascertained, also permits of evaporation when from any cause it occurs. These boxes are placed around the entire furnace in tiers, the tiers being, say, three feet apart, and the boxes in each tier about a similar distance from one another. The tiers may be carried up to the top of the furnace, if thought desirable, or to any height below that, and the boxes in each tier are arranged so as to alternate in position with the two adjacent boxes in the next tiers above and below. These boxes may be made accessible by platforms at the different tiers or in various other ways.

What we claim is—

1. In a furnace having a space in its wall

filled with gravel or like material, a horizontal water-pipe embedded in said filling and 35 perforated on its lower side, an external supply-pipe, as H, to contain water under pressure, and vertical pipes, as G, to supply water to the said horizontal water-pipe to fill said space by percolation, substantially as described. 40

2. In a furnace having a space in its wall filled with gravel or similar material, a horizontal water-pipe composed of disconnected sections having closed ends, said pipe being embedded in said filling and perforated, a supply-pipe, as H, and a series of external vertical pipes connecting said pipe H to each section of the horizontal water-pipe, substantially as described. 45

3. In a furnace having a space in the wall 50 filled with gravel or like material, and also having a water-pipe embedded in said filling for supplying water thereto by percolation, a series of observation-boxes in the furnace-wall open at their outer ends and having a 55 slot registering with the filled space in the wall, substantially as and for the purpose set forth.

In testimony whereof we have affixed our signatures in presence of two witnesses.

SAMUEL MCCLURE.
CHARLES F. PHILLIPS.
